UNITED STATES PATENT OFFICE.

MAYO BASS, OF GENEVA, NEBRASKA.

DESIGN FOR AN AUTOMOBILE-BODY.

45,250.

Specification for Design.

Patented Feb. 17, 1914.

Application filed February 7, 1913. Serial No. 746,964. Term of patent 14 years.

To all whom it may concern:

Be it known that I, MAYO BASS, a citizen of the United States, residing at Geneva, in the county of Fillmore and State of Nebraska, have invented a new, original, and ornamental Design for Automobile-Bodies, of which the following is a specification, reference being had to the accompanying drawing, forming part thereof.

The figures represent in side elevation and

front elevation respectively an automobile body showing my new design.

I claim—

The ornamental design for an automobile body, as shown.

MAYO BASS.

Witnesses:

JOHN K. WARING,
ROYAL WOODS.
